UNITED STATES PATENT OFFICE.

EDMUND H. SANDKUHL, OF STATEN ISLAND, NEW YORK, ASSIGNOR TO DAVID H. ZELL, INC., OF NEW YORK, N. Y., A CORPORATION OF NEW YORK.

LOCKING DEVICE.

Application filed July 5, 1923. Serial No. 649,420.

To all whom it may concern:

Be it known that I, EDMUND H. SANDKUHL, a citizen of the United States, and a resident of Staten Island, county of Richmond, and State of New York, have invented certain new and useful Improvements in Locking Devices, of which the following is a specification.

This invention relates to locking devices, and while of more or less general application, is particularly designed for the purpose of locking small safes or banks such as book form banks commonly supplied by large banking institutions to depositors for the collection of coins to be periodically credited upon the depositor's account.

It is the primary object and purpose of my present improvements to provide a device for the above purpose, which while exceedingly simple and inexpensive in its construction, will be highly effective to prevent opening of the bank or safe except by the custodian of the proper key.

In one embodiment of the invention I provide a locking rod rotatably mounted in any suitable manner upon opposite end walls of the safe. Upon the hinged side or cover plate of the safe a locking arm is secured, said arm and the rod having coacting means to retain said cover plate in closed position. Preferably, resilient means is provided to coat with the rod and yieldingly hold the same in locking position, said rod being formed at one end with means for engagement by spaced lugs of a suitable key whereby the rod may be rotated to release the locking arm on the cover plate.

It is also an object of my invention to provide a locking device of this character which may be used in conjunction with such banks or safes and applied thereto without necessitating numerous or expensive mechanical operations.

With the above and other objects in view, the invention consists in the improved locking device and in the form, construction and relative arrangement of the several parts as will be hereinafter more fully described, illustrated in the accompanying drawings and subsequently incorporated in the subjoined claims.

In the drawing wherein I have illustrated one simple and practical embodiment of the invention and in which similar reference

characters designate corresponding parts throughout the several views:

Figure 1 is a horizontal sectional view through the front portion of a book form bank or safe which is equipped with my improved locking device;

Figure 2 is a vertical section taken on the line 2—2 of Figure 1, the locking rod being shown in full lines in release position and in dotted lines in its locking position;

Figure 3 is a detail section taken on the line 3—3 of Figure 1 showing the parts in normal position;

Figure 4 is a similar view showing the locking rod in release position;

Figure 5 is a detail section taken on the line 5—5 of Figure 1;

Figure 6 is a detail exterior elevation; and

Figure 7 is a detail view of the key.

For purposes of illustration, I have shown my present improvements as applied to a coin receptacle or safe of the type generally known as a book form bank, in which the bank is provided with a body section and a cover section constructed and shaped, and provided with surface ornamentation in simulation of a book. It is, however, to be clearly understood that no limitations must necessarily be implied from the drawing, since in so far as the locking device itself is concerned, it will be appreciated from the following description that this device is of more or less general application and might be advantageously used as a locking means for receptacles or containers designed for many different purposes.

In the present instance, I have shown a receptacle or container body 5 having a cover plate 6 which is connected by means of suitable hinges (not shown) to the upper edge of one of the marginal walls of the body 5. This body and the cover plate are conveniently stamped from metal sheets, preferably of brass, and are lined upon the inner side faces of the walls thereof with thin sheets of copper indicated at 7 and 8 respectively.

Adjacent to the front marginal wall of the receptacle body the lining sheet 7 on the end marginal walls thereof is inwardly offset as at 9 and these off-set portions of the lining sheet are provided with openings 10 affording bearings for the ends of

the locking rod 11. This locking rod at one side thereof has a longitudinally extending flattened or plane face 12. With this flat face of the locking rod the obliquely inclined end edge 14 of a spring tongue 13 struck from the lining sheet 7 on the inner face of the front marginal wall of the receptacle body coacts to yieldingly hold the locking rod against rotation in the normal position illustrated in Figure 3 of the drawing.

The hinged top or cover plate 6 for the receptacle carries a locking arm 15 which may be formed as an extension of the lining sheet 8 and is disposed substantially at right angles to the plane of the cover plate. This locking arm or flange may extend longitudinally of the locking rod 11 for any desired distance. As illustrated, said arm or flange is shown of somewhat less length than the length of the flattened surface 12 on the locking rod and terminating in spaced relation to the resilient holding tongue 13.

At its free longitudinal edge the flange or arm 15 is provided with an inwardly directed angular bead 16. When the top or cover 6 is moved to a closed position upon the receptacle body the flange 15 enters the space between the front vertical wall of said body section of the receptacle and the locking rod 11 and engages upon the flattened face 12 of said rod which is disposed in the obliquely inclined plane illustrated in dotted lines in Figure 2 of the drawings. The bead 16 rides upon this flattened face of the rod as the flange 15 is forced downwardly whereby said rod is rocked or rotated until the inclined bead 16 is positioned below the lower edge of the flattened face 12. In such rocking or rotative movement of the rod 11, the upper edge of the flattened face 12 bears against the inclined edge 14 of the spring tongue 13 which readily yields under such pressure as shown in Figure 4 of the drawings. However, when the cover plate is fully closed and the bead 16 disposed in the position shown in Figure 2 of the drawing, the spring tongue 13 immediately acts to return the rod 11 to its normal position as shown in dotted lines in Figure 2, wherein it will be observed that the outer portion of this rod below the flattened surface 12 overlies the bead 16, thus effectually preventing the upward movement of the flange 15 and securely locking the cover plate in closed position.

At one of its ends the locking rod 11 is provided at diametrically opposite points with longitudinally extending grooves 17. This end of the rod is opposed to a disc 18 loosely mounted to rotate in an opening 19 formed in the end marginal wall of the case body. At its inner side this disc is formed

with a flange 20 overlying the edge of said opening and at diametrically opposite points the edge of the opening is provided with the notches or recesses 21. The disc 18 is also provided with opposed radially extending slots 22 opening upon the periphery of the flange 20 and terminating in spaced relation to the center of the disc. There is thus provided a central web 23 in the disc between the slots 22.

The key 24 as shown in Figure 7 of the drawing, has spaced lugs 25 between which the recess 26 is formed. Pins 27 project longitudinally from the lugs 25. At the outer side of each lug 25 a notch or recess 28 is formed. Before the key can be inserted to rotate the rod 11 the disc 18 is first rotated so that the slots 22 therein will register with the notches 21. The key is now inserted, the pins 27 being engaged in the groove 17 in the locking rod and the lugs 25 positioned in the slots 22 of the disc. The end wall of the receptacle body is then in line with the notches 28 of the key so that the key may be turned to rotate the rod 11 from its locking position shown in Figure 3, to the released position, illustrated in Fig. 4 of the drawing. As will be obvious, the flattened or plane surface 12 on the locking rod being then disposed in parallel relation with the flange 15, said flange is released so that the cover or top plate 6 of the receptacle can be raised or lifted to its open position.

From the foregoing description considered in connection with the accompanying drawing, the several features of my improved locking device will be clearly and fully understood. It will be appreciated that in view of the very simple form of the several elements employed, the device may be used in connection with collection banks or safes of the type referred to without necessitating any radical structural changes in such banks as heretofore manufactured or involving numerous and expensive mechanical operations. The arrangement of the spring tongue 13 with respect to the flattened surface 12 in the normal position of the locking rod is such that attempts to move said rod to its releasing position by means other than the proper key will be frustrated. Owing to the very simple mechanical construction of the several elements, it is apparent that the improved locking device will possess maximum durability and is not likely to readily get out of order.

I have herein illustrated and described one practical and satisfactory embodiment of my present improvements, but since it is possible that the principles herein involved might be exemplified in other alternative mechanical constructions, it is to be understood that I reserve the privilege of adopting all such legitimate changes in the form,

proportion and relative arrangement of the several parts as may be fairly embodied within the spirit and scope of the invention as claimed.

5. I claim:

1. In combination with a receptacle body and cover plate therefor, a locking device for said cover plate including a rod rotatably mounted upon the receptacle body, a 10 part carried by the cover plate, and means yieldingly holding said rod in a normal position in locking relation to said part to prevent opening movement of the cover, said part coacting with the rod when the cover 15 is moved to closed position to rotate the rod against the action of said holding means and said holding means, after the cover is closed, coacting with the rod to return it to locked position.
2. In combination with a receptacle body, and cover therefor, a locking rod rotatably mounted within the receptacle body and having a flattened surface on one side, a 25 flange carried by the cover and having a locking bead to coact with said flattened surface and rotate the locking rod when the cover is moved to closed position, and means yieldingly resisting such rotation of the locking rod and acting to return the same 30 to normal position in locking relation with the bead on said flange.
3. In combination with a receptacle body and cover therefor, a locking rod rotatably mounted within the receptacle body and having a flattened surface on one side, a 35 flange carried by the cover and having a locking bead to coact with said flattened surface and rotate the locking rod when the cover is moved to closed position, and a 40 spring tongue having an obliquely inclined edge to coact with the flattened surface of said rod, said tongue yieldingly holding the rod in locking relation to the bead on said flange.
4. In combination with a receptacle body 45

and cover therefor, a locking rod rotatably mounted at its ends within said body and extending in parallel relation to one of the marginal walls thereof, said rod having a flattened longitudinally extending surface 50 on one side, a spring tongue coacting with said flattened surface to yieldingly hold the rod against rotation with said surface in an obliquely inclined plane with respect to the marginal wall of the receptacle body and a 55 flange carried by the cover plate and having an angular bead to coact with said flat surface on the locking rod when the cover is moved to closed position and rotate said rod against the action of said spring tongue, 60 said tongue resisting such rotation and returning the rod to its locking position with relation to the bead on said flange.

5. In combination with a receptacle body and cover therefor, a locking rod rotatably mounted at its ends within said body and extending in parallel relation to one of the longitudinal walls thereof, said rod having a flattened longitudinally extending surface 70 on one side, a spring tongue coacting with said flattened surface to yieldingly hold the rod against rotation with said surface in an obliquely inclined plane with respect to the marginal wall of the receptacle body, and a flange carried by the cover plate and having an angular bead to coact with said flat surface 75 on the locking rod when the cover is moved to closed position and rotate said rod against the action of said spring tongue, 80 said tongue resisting such rotation and returning the rod to its locking position with relation to the bead on said flange, said locking rod being provided at one of its ends with key engaging means whereby said rod 85 may be turned to its releasing position against the action of said spring tongue.

In testimony that I claim the foregoing as my invention, I have signed my name hereunder.

EDMUND H. SANDKUHL.
